UNITED STATES PATENT OFFICE

2,116,658

SWITCH CABINET

Harrison J. L. Frank, Detroit, Mich.

Application January 20, 1936, Serial No. 59,875

9 Claims. (Cl. 200—114)

This application relates to fused switch cabinets, to panels thereof made up of two or more fused switches, and to fused switches generally of the character disclosed in Reissue Patent No. 5 17,910 of April 2, 1935 granted to Harrison J. L. Frank.

A fused switch cabinet includes a sheet metal box containing a panel of two or more fused switches, the panel comprising a duplex receptacle base, each receptacle of which receives a fuse carrier plug or head, each receptacle and its head comprising a switch.

One invention hereof relates to a novel manner of mounting the panel base in the box.

15 Another invention relates to means preventing interchange of the heads in the panel receptacles; were such means omitted, a head carrying a large capacity fuse might easily be plugged into a receptacle controlling a circuit whose maximum load is to be that of a smaller capacity fuse, with 20 consequent deleterious results.

Another invention relates to the provision, in the heads, of slots on opposite sides of end ribs, which slots provide vents for the interiors of the 25 switches, ways for test leads, and adequate clearance between switch parts of opposite polarity.

Still another invention relates to the provision, in the heads, of weakened portions or "knock-outs" which may be knocked out if desired to provide 30 vents for the interiors of the switches and windows through which it may be determined by observation alone whether or not fuses are disposed in the switches.

Still another invention relates to features of 35 mounting for conductor parts of the switches whereby economy of manufacture is enhanced.

Still another feature relates to novel arrangements of conductor parts of the switches whereby 40 flexibility of use of the panel is enhanced.

45 For an understanding of the parts disclosed in the appended drawings, reference should be had to the following specification.

In the drawings,

Fig. 1 is a front elevation view of a switch cabinet containing a panel with two switches, one of the heads being removed for purposes of exposing the base of the switch including such head;

Fig. 2 is a fragmentary section view of a switch;

Fig. 2a is a side view of a head, per se;

50 Fig. 3 is a fragmentary back view of a head per se;

Fig. 4 is a fragmentary enlarged front view;

Figs. 5 and 6 are side and front views, relating to mounting means for the panel;

55 Fig. 7 is a detail view of a fuse socket;

Fig. 8 is a back elevation view of the panel per se;

Fig. 9 is a section on line 9—9, Fig. 8;

Figs. 10 and 11 show different uses of the panel;

Fig. 12 is a perspective view of the panel per 5 se from the back thereof;

Figs. 13-16 are perspective views of conducting parts of the panel;

Fig. 17 is a section on line 17—17, Fig. 8.

Referring to the drawings, it will be seen that 10 the fused switch cabinet of this application includes a box 5 containing a panel comprising a unitary block 6 formed with two receptacles disposed side by side, each receptacle being cup-shaped and being adapted to receive a fuse carrier 15 or head 7.

The panel may be mounted in the cabinet in a convenient and facile manner. It will be observed that the rear wall of the box is provided with tongues 8 and a screw 9, and that the rear wall 20 of the panel is provided with ears 10 and a slot 11. When a panel is to be mounted, the screw 9 is threaded out to a considerable extent and the panel is manipulated so that the screw 9 is received in the slot 11 of the panel. Then the 25 panel is pushed up as far as it will go until the ears 10 clear the tongues 8, after which the panel is pushed against the back of the box so that the ears 10 may be received behind the tongues 8, whereupon the panel is permitted to drop slightly 30 and the screw 9 is tightened up.

Surrounding the panel is a masking plate 14 of conventional construction and adapted to close the front of the box is a hinge cover 15.

In back of slots 19 formed in the back of each 35 receptacle, and thus accessible from the front of the receptacle, are disposed receptacle contacts 20. For mating with the receptacle contacts, there are provided prongs 21 forming terminals of J-shaped contact straps 22 of copper or the 40 like, whose bights are secured to the heads 7 by the spun-over ends of embedded rivets 23, there being spring clips 24 between the bights and the heads to help secure in place cartridge fuses 25 connecting aligned contacts 22, the ferrules of 45 the fuses being received within the bights and the spring clips of these contacts.

On the fronts of the heads are handles in the form of pull rings 27 secured to the heads by cotter straps 28, which go through the heads and 50 terminate in portions disposed in wells 29 in back of the heads.

When a switch is to be closed, a fuse carrying head is plugged into a receptacle; the contacts 22, connected by fuses 25, have their prongs 21 55

fitted through the slots 19 of the receptacles to engage and make contact with the receptacle contacts 20 in back of these slots 19. When a switch is to be left open, the head is removed and reversed 180° and reinserted into the receptacle, but with the fuses and contacts exposed and projecting towards the front of the cabinet.

Each receptacle is provided in its interior with back wall slots 30 and receptacle end wall slots 31. Cooperating with the slots 30-31 are ribs 32-33 projecting respectively from the back and from each end wall of the head, the ribs 32-33 fitting into the slots 30-31 respectively. These ribs function not only as guiding and barrier ribs, but also, by virtue of the fact that the ribs and slots of one switch are of slightly different configuration from those of its neighboring switch, serve to prevent improper interchange of heads. It will be observed that the end slots and end ribs of one switch are deep and narrow, whereas the end slots and end ribs of the adjacent switch are shallow and wide; a head having shallow-wide ribs cannot fit into a receptacle formed with deep-narrow slots, and vice versa, with the result that a head cannot be plugged into a receptacle other than the one for which it is intended.

For reinforcing and barrier continuing purposes, the ribs 32 of a head are connected by the walls of the well 29 receiving the end of the cotter strap.

Adjacent and separated by each end rib 33 are slots 36. The slots provide vents from the interior of the switches to outside the same; the slots provide ways for test leads whose terminals may be caused to engage contact parts of the heads; and the slots, together with the barriers formed by the end ribs 33 therebetween, cooperate to provide greater creepage paths between the opposite polarity contacts of the heads than would be the case were the slots not present.

In the center of each head and on opposite sides of the cotter strap 28 which mounts the pull ring handle of each head are weakened portions or knock-outs 37. The opening created by removing a knock-out will provide a large vent for the interior of the switch and in addition will provide a window through which may be viewed the interior of the switch so that it can be determined by mere observation whether or not certain of the contacts are connected by fuses 25.

The switches are connected in circuit through fuses disposed in socket shells 38 of conducting material disposed in depressions or sockets 39; the wall of each socket hugs its shell closely except where shells are adjacent, in which case the walls are cut away, as at 40, between points X, with the result that the requisite minimum creepage path between shells of opposite polarity is preserved even though the center-to-center distance between shells is below what was hitherto considered a safe minimum.

The receptacle contacts 20 are formed as lugs of straps 42-42g, 42'-42g' welded to each other and transversely directed from straps 43-43g; certain of these straps 43-43g are apertured to receive axial shanks of terminal connectors 44 having tapped holes receiving screws 45; others of these straps 43-43g, which do not have connectors 44 associated therewith, have tapped holes receiving screws 45a whose heads form center or tip contacts for the socket shells 38; it will be observed that each unit comprising a receptacle contact set, a strap, and a terminal connector, is mountable on the block merely by placing the unit against the back of the block in a proper

place and sliding the connector end thereof through an end slot of the block, and each unit is securely mounted on insulation ledges 46-47, formed integral with the block 6, by a single screw 45 or 45a, which features enhance the simplicity and economy of manufacture of the panel.

The panels are so constructed that various manners of using the switches thereof may be attained. For example, by connecting straps 42d-42g through an insulated conductor 50 whose ends are hooked around screws 51 mounting the conductor 50 on straps 42d-42g, and by interconnecting straps 43e-43f through a conductor 52 held in place by the threading of certain screws 45a into tapped holes thereof, all as illustrated in Fig. 8, it is possible to connect outside lines to the panel to obtain two uses of the panel parts, as shown in Figs. 10 and 11, which differ from uses obtainable when these parts 50 and 52 are omitted.

In Fig. 10 there is shown an arrangement wherein branch circuit conductors C53, C54, D53, D54 are connected to socket shells 38 in a suitable manner, as by means of socket shell connecting screws 55 (Fig. 7), wherein branch circuit conductors C55, D56 are connected in circuit by connectors C44, D44, wherein branch circuit conductors are connected in circuit by connectors A44, wherein main feed conductors are connected in circuit by connectors B44, and wherein fuses in the socket shells connect screws 45a-55 in pairs; so connected, the panel may be used with switch I as a main switch and with switch II as a branch switch, the main switch I controlling the connection between the main feed circuit and all other circuits and with the branch switch II controlling only the branch circuit A.

If, as is shown in Fig. 11, the conductors C56, D56 are the main feed conductors, and all other conductors are branch conductors, switch I will control branch circuit conductors B and switch II will control branch circuit conductors A, and branch circuit conductors C53, C54, D53, D54 will be permanently connected to the feed conductors 45 and be independent of the switches I and II.

Other uses may be attained by varying the connections, with the parts arranged as shown, and still other uses may be attained by varying the arrangements of the parts 50-52 and the connections.

I claim:

1. A plug and receptacle switch comprising a receptacle having adjacent opposite polarity contacts, a plug adapted to be disposed therein and having on its back surface back projecting contacts mating with the receptacle contacts, and having on its end wall end slots aligned with the plug contacts to provide vents for the interior of the receptacle and ways to the plug contacts for test leads, and also to provide an extraordinary creepage path on the end of the plug between the plug contacts.

2. A cup shaped insulating block having a slot in its bottom wall, and a slot in its end wall, and an end ledge, a conductor strap disposed in the end slot, and having a portion resting on the ledge, and a portion disposed against the under surface of the block, a conductor terminal connector secured to the portion of the strap disposed on the ledge, a contact secured to the portion of the strap disposed against the under surface of the block and accessible for receiving a prong to the front of the block through the block bottom

wall slot and a single screw for securing the strap, its connectors, and its contact in place.

3. A duplex receptacle block having eight contacts arranged in two groups each of which includes two pairs, two switch plugs, each having a group of two pairs of contacts, the arrangement providing two relatively independent switches each controlling one group comprising two pairs of contacts, two in each pair, the contacts being arranged with four at one end of the block and four at another end of the block, there being one contact of each pair in each line of four, the contacts of one line of four being electrically independent of each other and each having a conductor terminal connector, the outside contacts of the other line of four being electrically interconnected and the inside contacts of such other line of four being electrically interconnected, with the inside contacts being electrically independent of the outside pair, a fuse near each contact of the second line of four and connected at one end to one contact of that line of four and connected at its other end to a conductor terminal, and two conductor terminals, other than the four connected to the four fuses, with one connected to one of an inside pair of contacts and with the other connected to one of an outside pair of contacts.

4. In a receptacle, a plug disposed therein and having conducting parts on its back and having, on its end, slots aligned with the conducting parts and running from front to back of the plug providing access to the conducting parts from the front of the plug and providing an extraordinary creepage path on the end of the plug between the conducting parts.

5. A plug and receptacle switch comprising a cup shaped receptacle normally closed by the plug and containing a fuse, and a knockout on the plug front aligned with the fuse which may be knocked out to provide a vent and an observation hole or window for the receptacle.

6. A cup shaped insulation block having a slot in its bottom wall, and a slot in its end wall, and an end ledge, a conductor strap disposed in the end slot, and having a portion resting on the ledge, and a portion disposed against the under surface of the block, a conductor terminal connector secured to the portion of the strap disposed on the ledge, a contact secured to the por-

tion of the strap disposed against the under surface of the block and accessible for receiving a prong to the front of the block through the block bottom wall slot and a single screw for securing the strap, its connectors, and its contact in place, 5 a plug fuse socket shell in the block, and a screw passing through the bottom of the shell and the block and threaded into the strap.

7. A cup shaped insulation block having a slot in its bottom wall, and a slot in its end wall, 10 and an end ledge, a conductor strap disposed in the end slot, and having a portion resting on the ledge, and a portion disposed against the under surface of the block, a conductor terminal connector secured to the portion of the strap disposed on the ledge, a contact secured to the portion of the strap disposed against the under surface of the block and accessible for receiving a prong to the front of the block through the block bottom wall slot and a single screw for securing 15 the strap, its connectors, and its contact in place, a plug fuse socket shell in the block, and a screw passing through the bottom of the shell and the block and threaded into the strap, the part of the screw within the shell providing a tip contact in 20 the shell of the same polarity as the strap.

8. A cup shaped insulation block having a slot in its bottom wall, a conductor strap having a portion disposed against the under surface of the block, a contact secured to the portion of the 30 strap disposed against the under surface of the block and accessible for receiving a prong to the front of the block through the block bottom wall slot, a plug fuse socket shell in the block, and a screw passing through the bottom of the shell 35 and the block and threaded into the strap.

9. A cup shaped insulation block having a slot in its bottom wall, a conductor strap having a portion disposed against the under surface of the block, a contact secured to the portion of the 40 strap disposed against the under surface of the block and accessible for receiving a prong to the front of the block through the block bottom wall slot, a plug fuse socket shell in the block, and a screw passing through the bottom of the shell and 45 the block and threaded into the strap, the part of the screw within the shell providing a tip contact in the shell of the same polarity as the strap.

HARRISON J. L. FRANK. 50
